UNITED STATES PATENT OFFICE.

RUDOLF GAHL, OF MIAMI, ARIZONA.

ORE LEACHING AND SETTLING TANK.

1,341,208.

Specification of Letters Patent.

Patented May 25, 1920.

Application filed May 23, 1918. Serial No. 236,174.

To all whom it may concern:

Be it known that I, RUDOLF GAHL, a citizen of the United States, residing at Miami, in the county of Gila and State of Arizona, 5 have invented certain new and useful Improvements in Ore Leaching and Settling Tanks, of which the following is a specification.

This improvement refers to settling tanks 10 or reservoirs especially in connection with so-called continuous decantation processes for leaching finely divided ores with suitable chemicals.

Such processes require the repeated settling 15 of large quantities of fine ore pulp, and their success depends largely on the proper design and construction of the settling tanks.

Heretofore settling tanks have been used 20 whose action depends on the proper slope being given to the conical lower portion on which the settled material slides to the spigot in the bottom, through which the thickened material is discharged, most of the liquid portion of the pulp (water or solvent) discharging 25 over an overflow edge into suitable launders. Where large capacities are required, it has heretofore been necessary to employ batteries of such tanks. Tanks of as large diameter as 200 feet and having a 30 more slightly inclined bottom in which the movement of settled material is assisted by mechanical raking mechanism have also been successfully used.

While settling tanks of various designs are 35 in use, none are large enough where many thousands of tons of slime are to be handled per day, inasmuch as they require a very large floor space, and their construction is too expensive to be considered in cases where 40 large amounts of very low grade slime have to be leached.

I have found a way of economically constructing large sized settling reservoirs, the principal features of which will be described 45 below.

Reservoirs of my design may be built in any location that offers sufficiently large tracts of fairly level ground. Where naturally level ground is not available, the 50 products of ore reduction plants, i. e., tailings or slag may be utilized to form level places by filling up ditches, gulches, etc. It is not necessary that the ground be impervious as it will soon become so after being 55 saturated with slimes.

After a fairly level piece of ground has

been secured, walls of suitable height are built around the places that are to serve as reservoirs. This can, in the neighborhood of ore dressing works, generally be most 60 cheaply accomplished by depositing sand tailings along such lines. I prefer to have the reservoirs thus formed of rectangular shape, rather long and narrow, for instance, for a large installation, a size 800 ft. by 100 65 ft. for individual reservoirs may be used.

In actual operation the reservoir is kept filled with slime, the thicker portion of which stratifies near the bottom, while the lighter layers occupy the high levels. On 70 top of the stratified slime there is generally a layer of clear solution. A dredge comprising a raft of suitable design floats on the ore pulp and carries means for pumping or otherwise transferring the thickened pulp 75 that has accumulated near the bottom. I find that the movement of the dredge formed by placing suitable pumping machinery on the raft, does not agitate the pulp settling in the reservoirs enough to interfere to any 80 practically noticeable extent with the settling action taking place.

If elevators are used for lifting the thickened pulp from the bottoms of the reservoirs to a point above the solution level, the 85 travel of the elevator buckets causes excessive agitation if not confined by a casing. If, however, a casing is provided which limits the agitation to its inside, and communicates with the contents of the reservoir only 90 at the bottom where it forms an intake for the thickened pulp, the agitation caused by the traveling buckets is localized and will not interfere with the settling operations.

If centrifugal pumps or air-lifts are used 95 for the purpose of pumping the settled pulp, the pump intake and the air lift pipes prevent lateral extension of the agitation and no special provision for this purpose is necessary.

A settling plant of the kind above described is shown in the accompanying drawings, in which—

Figure 1 is a vertical transverse section through a settling tank.

Fig. 2 is a partial plan view of the float shown in Fig. 1.

Fig. 3 is a diagrammatic plan view of a system of tanks, the flow of settled slime being indicated by solid lines with direction 110 indicating arrows, the flow of overflow liquid being similarly indicated by dotted

lines; and the flow of material into the various tanks being indicated by curved arrows.

Fig. 4 is a plan of Fig. 1.

Referring to Fig. 1, the tank 1 is shown as formed mainly of tailings, planking or other retaining means being used only at the upper edges. On one of the sides or ends of the tank is provided a feed launder 2, delivering into an open-bottomed trough 3. At the other side of the tank is an overflow launder 4. Arranged to float in the tank is a raft 5, of any suitable construction on which is mounted a device for raising the settled slimes, shown in this instance as an air-lift pipe 6, to which compressed air is delivered by a pipe connection 7, to which air is fed by a flexible hose 8 of any desired length. The air-lift pipe 6 is provided with a laterally extending delivery chute 8, through which the slimes are discharged into a launder 9. The raft may be moved by ropes fastened to either side and reaching to the two respective ends of the tank where they are carried by winding drums, this propelling mechanism not being shown. The walls of the tanks are made of tailings and nothing need usually be done to make these tailings impervious, as the fine slime soon enters and fills the pores. In case further precautions are deemed to be necessary, an oil heavier than water such as crude coal-tar may be spread over the bottom of the tank and will form an effective seal.

The feed launders may be located in the sides or ends of the tanks, as circumstances may dictate, such an end feed being indicated in tank No. 6 of Fig. 3. In such instances, the floating dredge may be supplemented by a stationary pumping device, to handle the main portion of the slimes which in that case will be settled out near the point of delivery.

In Fig. 3 is diagrammatically shown an application of a system of tanks for the recovery of copper from tailings by leaching the same with acid and precipitation by powdered limestone according to the method described in my application Serial No. 186,411, filed Aug. 15, 1917.

As will appear from the accompanying flow sheet, the slimes are delivered to settling tanks 1 and 2 from which the clear water is sent back to the mill. The settled slimes are then subjected to a series of leaching operations in interconnected decantation tanks 3,

4, 7, 8 and 9, the leaching liquor being added in a special reaction tank 5. The final leaching occurs, as shown in tank 3, from which the solution overflows into a clarifying tank 6, from which in turn the clarified solution goes to the limestone agitating tank 11, from which the agitated mixture of solution and limestone passes to tank 10 from which the limestone having the metal values deposited thereon is removed and sent to the smelter. From the tank 9, the barren tailings are sent to waste.

I claim:

1. An ore settling tank of considerably greater length than width adapted to contain large quantities of ore and liquid, a liquid overflow launder near the top of the tank, means for delivering slimes into the tank, means for elevating and delivering settled material from the bottom of the tank, said means comprising a float, and slime-elevating and delivering apparatus carried thereby.

2. An ore settling tank adapted to contain large quantities of ore and liquid, a liquid overflow launder near the top of the tank, means for delivering slimes into the tank, means for elevating and delivering settled material from the bottom of the tank, said means comprising a float, and slime-elevating and delivering apparatus carried thereby.

3. An ore settling tank adapted to contain large quantities of ore and liquid, means for delivering slimes thereinto, means for elevating and delivering settled material from the bottom thereof comprising a float, and slime-elevating and delivering apparatus carried thereby.

4. A tank as claimed in claim 2 built up of ore tailings.

5. A tank as claimed in claim 2 built up of ore tailings waterproofed by oil.

6. An ore treating plant comprising a series of tanks as claimed in claim 2, and means for interconnecting the tanks comprising launders for separately delivering settled slimes and liquid.

7. An ore settling tank, as claimed in claim 2, in which the means for delivering slimes, for removing slimes and for overflow of clear water are arranged to permit continuous operation.

In testimony whereof, I affix my signature.

RUDOLF GAHL.
